UNITED STATES PATENT OFFICE.

DANIEL SHALES AND NEWMAN McCULLY, OF BOSTON, MASSACHUSETTS.

DESIGN FOR PARLOR FURNITURE.

Specification forming part of Design No. 6,891, dated September 23, 1873; application filed June 30, 1873.
[Term of Patent 3½ years.]

To all whom it may concern:

Be it known that we, DANIEL SHALES and NEWMAN McCULLY, both of Boston, in the county of Suffolk and State of Massachusetts, have invented and produced a new Design for Parlor Furniture, of which the following is a full, clear, and exact description, reference being had to the accompanying photograph making part of this specification.

Our design consists in the back of the frame of a chair, sofa, or other article of furniture, provided at its center with an ornamental device, representing one or more shields with a rosette above it, and surmounted by carved leaf-work, the back of the frame also being provided with a pair of rosettes, one on each side of the center device, and having a raised veneered panel under each rosette.

In the said photograph, A represents the back of the frame of a chair, sofa, or other piece of parlor furniture, provided at the center of its top with a device, a, consisting of carved leaf-work surrounding the sides and top of a rosette, b, below which are placed two shields, c d, one above the other, the lower shield being provided or not with a Grecian drop under either side. On each side of and

equidistant from this central device is a rosette, a, beneath which is formed a raised veneered panel, h. i is a bracket connecting each of the inner ends of the arm-rests k with one of the upright standards l of the central portion of the back of the frame. The arm-post m supporting the arm-rest n of the gentleman's chair is of Grecian pattern, as also the arm-brace o of the lady's chair, the design of the whole being exceedingly unique and ornamental.

What we claim as our invention, and desire to secure by Letters Patent, is—

The design for the frame of the back of a chair, sofa, or other article of furniture, consisting of one or more shields, c d, surmounted by a rosette, b, and carved leaf-work a at its center with a rosette, e, on each side thereof, and a veneered panel, h, under each rosette e, substantially as herein shown and described.

Witness our hands this 26th day of June, A. D. 1873.

DANIEL SHALES.
NEWMAN McCULLY.

In presence of—
N. W. STEARNS,
C. E. HANSON.
